PIN CONNECTOR

Lloyd Mancini, Hershey, Pa., assignor to Berg Electronics, Inc., New Cumberland, Pa., a corporation of Pennsylvania

Filed Apr. 27, 1964, Ser. No. 362,575

2 Claims. (Cl. 339—256)

This invention relates to electrical connectors, particularly those of very small size for pin type terminals. Conventional connectors may be and have been made in small sizes, but as the size is reduced the connector becomes less satisfactory. The present invention provides a construction which is especially suitable for miniature connectors in that it combines desirable performance and quality characteristics with low cost.

A principal object of the invention is to provide a new and improved connector for pin type terminals which can be made out of very thin metal stock and in miniature size.

Other and further objects of the invention will be apparent from the following description and claims and may be understood by reference to the accompanying drawings which by way of illustration show a preferred embodiment of the invention and what I now consider to be the best mode of applying the principles thereof. Other embodiments of the invention may be used without departing from the scope of the present invention as set forth in the appended claims.

In the drawings:

FIGURE 1 is a plan view of a strip of terminals illustrating the several steps in the making of the same;

FIGURE 2 is a plan view of a single connector before it is crimped on the electrical conductor;

FIGURE 3 is an enlarged side elevational view of a single connector;

FIGURE 4 is an enlarged sectional view taken along the line 4—4 of FIGURE 3;

FIGURE 5 is an enlarged sectional view taken along the line 5—5 of FIGURE 3;

FIGURE 6 is an enlarged sectional view taken along the line 6—6 of FIGURE 2;

FIGURE 7 is a side elevational view of the connector assembled to a pin type terminal;

FIGURE 8 is a sectional view taken along the line 8—8 of FIGURE 7; and

FIGURE 9 is an enlarged sectional view taken along the line 9—9 of FIGURE 2.

As illustrated in FIGURES 2 and 3, an electrical connector embodying the invention is formed from an integral piece of thin sheet metal to provide a ferrule 20 for crimping onto an electrical conductor and an elongated socket 22 for telescopically receiving and yieldably holding a pin type terminal having flat sides, such as a square pin 24. The socket 22 comprises aligned spaced sleeve portions 26 and 28 interconnected by oppositely disposed longitudinally extending spring portions 30. As illustrated in FIGURES 4 and 8, the sleeve portions 26 and 28 have an inner cross section matching that of the pin terminal 24 and the interior corners of the sleeve portions are relieved as at 32 so as to eliminate any interference between the interior corners of the sleeve portions 26 and 28 and the sharp corners of the pin 24.

The spring portions 30 are inwardly bowed intermediate their ends so as to provide single curvature contact surfaces presented toward the axis of the socket and more closely spaced than the corresponding inner surfaces of the sleeve portions for engagement with the flat sides of the pin terminal. The spring portions 30 are substantially more flexible than the sleeve portions 26 and 28, and the contact surface areas 34 of the spring por-

tions 30 are coined. The coining reduces the thickness of the metal at the contact surface areas, improves the spring characteristics thereof, and provides a desirable contact surface for engagement with the flat side of the pin 24. The coining widens the spring portions 30 at the middle as illustrated in FIGURE 3 and, as illustrated in FIGURE 9, results in ridges 40 which provide guides along the side edges of the spring portions for guiding the pin terminal during insertion.

The interior cross section of the sleeve portions 26 and 28 is made slightly larger than the cross section of the pin 24 so that there is no interference between the pin and the sleeve portions 26 and 28, although there is a close fit. The spacing between the bowed center portions 34 of the spring portions 30 is less than the minimum cross section of the pin 24 so as to provide a frictional fit between the contact areas 34 and the sides of the pin 24. Since the spring portions 30 are relatively flexible, they will provide area contact with the sides of the pin 24 even though the spring portions are bowed.

The wire crimping ferrule 20 may be made of any conventional construction and is adapted to be crimped around the bared end of a wire so as to integrate the connector with an electrical conductor. The flexibility of the spring portions 30 assures that the contact surface areas 34 will seat on the flat sides of the pin 24. The insertion of the pin into the socket of the connector of course will tend to open up or spread the contact surface areas 34. However, due to the type of construction used, this will tend to elongate the socket rather than tend to unwrap or open up the sleeve portions 26 and 28.

The connectors may be made in strip form from metal strip stock, such as $\frac{3}{4}$ hard Phosphor bronze, or any other material suitable for making electrical connectors, and the stock may be plated with a suitable plating, such as tin or gold. In making the connectors of strip stock, the strip is subjected to a series of blanking and forming operations so as to provide a ferrule portion 20, a connector portion 22, and a locating portion 50. The ferrule portion 20 is bent into U-form as is convention, for crimping around the bared end of the wire, and the connector portion 22 is folded or bent as to provide the sleeve portions 26 and 28 having interior cross sections which are substantially square. However, before the connector portion 22 is folded to form the finished connector, the portions which form the spring portions 30 are coined to provide the contact areas 34 and ridges 40 previously referred to. By way of example, I have found that this type of construction lends itself to being made in a size for use with a pin terminal having a cross section of .025 inch, and in such case the interior cross section of the sleeve portions 26 and 28 preferably is .027 inch. The strip stock used for making such connector was .010 $\frac{3}{4}$ hard Phosphor bronze with a gold over nickel plating.

While I have illustrated and described a preferred embodiment of my invention, it is understood that this is capable of modification and I therefore do not wish to be limited to the precise details set forth but desire to avail myself of such changes and alterations as fall within the purview of the following claims.

I claim:

1. An electrical connector formed from an integral piece of thin sheet metal to provide a ferrule for crimping onto an electrical conductor and an elongated socket for telescopically receiving and yieldably holding an essentially square pin terminal, said socket comprising aligned spaced square sleeve portions solely interconnected by oppositely disposed and longitudinally extending spring portions extending between corresponding aligned sides of said sleeve portions, said sleeve portions

having an inner cross section matching that of the pin terminal, said spring portions being inwardly bowed toward each other intermediate their ends so as to provide single curvature contact surfaces presented toward the axis of the socket and more closely spaced than the corresponding inner surfaces of said sleeve portions for engagement with the flat sides of the pin terminal, said contact surfaces having a width greater than that of said pin, said spring portions being more flexible than said sleeve portions whereby insertion of the pin in the 10 socket flexes said spring portions apart so as to move said sleeve portions apart longitudinally.

2. A connector according to claim 1 wherein the contact surface areas of said spring portions are coined, are more flexible than the ends of said spring portions, and 15 are provided with inwardly extending guide ridges along

the side edges of said spring portions for guiding the pin terminal during insertion between said spring portions.
